CIRCUIT BREAKER DEVICES

Norbert R. Benchemoul, Paris, France, now by change of name Norbert R. Beynard

Application May 4, 1953, Serial No. 352,673

Claims priority, application France May 7, 1952

9 Claims. (Cl. 317—11)

In my U. S. patent application Serial No. 302,789, filed August 5, 1952, for "Liquid Resistance Electrical Apparatus," which became Patent 2,649,526, dated August 18, 1953, I have described an apparatus through which an electric current is intended to be passed and which includes at least two electrodes placed opposite to each other and enclosing a chamber of small volume which communicates with a vessel containing a conduction liquid, by means of at least two channels which present a certain resistance to the passage of the liquid.

An apparatus of this kind operates in the following manner:

As long as the strength of the current which passes through the chamber between the two electrodes does not exceed a certain value, known as the "threshold" value, the conducting liquid remains in the fluid state and the apparatus offers only a very small resistance to the passage of the current. On the other hand, as soon as the current density exceeds the threshold value, there results a vaporisation of the liquid in the said chamber and expulsion, at least to some extent, of the liquid towards the vessel, in such a way that the resistance offered to the passage of current between the electrodes increases rapidly and thus there is produced, at least momentarily, a limitation of the current.

In actual fact, the liquid which has been expelled can only return slowly from the vessel into the chamber because of the resistance to the flow of the liquid offered by the channels.

The present invention has for its object the application of such an apparatus to the production of an excess current circuit-breaker device.

The circuit-breaker device in accordance with the invention includes, in series with the supply circuit of an installation, at least one apparatus comprising two oppositely arranged electrodes forming between them a chamber of small volume, which chamber communicates with a vessel containing a conducting liquid, by means of passages offering a certain resistance to the flow of the liquid and, in shunt to the said supply circuit, between the said apparatus and the installation, the winding of a minimum current circuit-breaker designed to open the said supply circuit.

When for any particular reason, the current taken by the installation increases to an abnormal extent, there is produced in the apparatus, at least a partial vaporisation of the conduction liquid, such that the resistance between the electrodes rises to a value much higher than that which obtains when the chamber is entirely filled with liquid.

In consequence, the voltage at the terminals of the coil winding falls away sharply and this results in the opening of the minimum current circuit-breaker. At the same time, the introduction of this high resistance into the circuit diminishes the value of the overload current so that the breaking of the supply circuit by the minimum current circuit-breaker can be effected when the current has fallen

2

to a reasonable value which considerably simplifies the circuit-breaker problem.

There is thus obtained the result, to all appearances paradoxical, that an installation is protected against excessive current overload by means of a minimum current circuit-breaker which, furthermore, breaks the current, not when this is a maximum as is the case with normal circuit-breakers, but when this current has fallen back to a value which may even be less than the normal current value taken by the installation.

The advantages of such a circuit-breaker arrangement are immediate, for it is clear that, in these circumstances, the contact studs of the circuit-breaker device run little risk of being damaged at the moment when they separate and that it is unnecessary, because of the low value of current concerned, to provide a blow-out of the electric arc which is likely to be produced between these studs. In addition, because of the reduction in the current overload value before the breaking of the circuit, the installation itself is thus protected against high excess voltages which quite usually occur when the current is broken at the moment of its maximum value.

In one convenient form of embodiment of the invention, the chamber enclosed by the electrodes is provided with small vent holes which allow a partial escape of the vapour which is given off. In this way, the expulsion of the liquid contained in this chamber into the vessel can be slowed down, thereby ensuring a sharply progressive reduction in the values of the overload current.

30 There is no accessory device which is absolutely necessary to the operation of this circuit-breaker device. However, in order to permit of action being taken at the installation when an overload tends to occur and to increase, by reason of a fault which becomes more serious, 35 the circuit-breaker in accordance with the invention may be completed by a warning device. In practice, in such a way, a pulsating condition tends to be set up in the apparatus, since a partial vaporisation of the liquid in the chamber, resulting in a reduction in the strength of the current, is followed each time by a return of this liquid from the vessel to the chamber and so on. At a point in the circuit after the apparatus, and particularly at the terminals of the winding of this circuit-breaker, there are thus produced pulsatory voltages which can be used to 40 operate a winking device. Before the circuit is broken, 45 the occurrence of this winking thus warns the user of the existence of an abnormal condition.

The liquid used in the apparatus may with advantage consist of an electrolyte and the apparatus is preferably 50 constructed in such a manner that the internal voltage drop between the electrodes is less than the polarising voltage so as to avoid any electrolytic phenomena in the apparatus. Very large number of electrolytes are suitable for this use, and in particular use may be made of 55 solutions of potash or potassium carbonate.

The circuit-breaking device in accordance with the invention may be applied to all single or polyphase alternating current distribution systems and, as will be seen later, it may be provided to protect one or more phases of such 60 a distribution system.

The blade contact of the minimum current circuit-breaker may be arranged in such a manner that they ensure the disconnection of all the cables of the distribution system, in order to prevent a part of the installation or 65 of the apparatus being left under voltage after the circuit is broken.

The circuit-breaker device in accordance with the invention is particularly suitable for installations which include motors, the starting of which is effected by the 70 intermediary of a liquid rheostat resistance. In this case, the chamber formed between the electrodes of the circuit-breaker device in accordance with the invention,

is in relation with the same vessel as that which contains the liquid rheostat starting resistance of the motor and, preferably, in the upper portion of that vessel.

In addition to its role as a circuit-breaker, the device in accordance with the invention, has also two supplementary functions. In the first place, it constitutes an apparatus for controlling the level of the liquid in the common vessel. In addition, it provides thermostatic control of the installation. In practice if, in consequence of a detective operation of the liquid resistance rheostat, the temperature of this liquid increases to an abnormal extent, the threshold current necessary for the operation of the circuit-breaker device in accordance with the invention, decreases and this latter comes into operation in time to prevent adverse effect on the installation.

The description which follows in respect of the attached drawings (which are given by way of example only and not in any manner by way of limitation) will make it quite clear how the invention may be carried into effect, the special features which are referred to, either in the drawings or in the text, forming clearly a part of the present invention.

Fig. 1 is a diagrammatic representation of a simple form of embodiment of a device in accordance with the invention.

Figs. 2 and 3 are diagrams intended to make the operation of the apparatus shown in Fig. 1 quite clear.

Fig. 4 is a vertical cross-section of a combination of a device in accordance with the invention with a liquid resistance rheostat, provided, for example, for starting up an electric motor.

Fig. 5 is a cross-section through V—V of Fig. 4.

Fig. 6 is an explanatory diagram showing the operation of the apparatus shown in Fig. 4.

Fig. 7 shows schematically the application of a device in accordance with the invention to the case of a three-phase supply system.

Fig. 8 is a cross-section through VIII—VIII of Fig. 7.

And finally Fig. 9 is a diagram of the application of the device in accordance with the invention to the case of a two-phase four-wire supply system.

The installation 1 shown in Fig. 1 is supplied with alternating current from the terminals 2 of a single-phase distribution system through the intermediary of a circuit-breaker device in accordance with the invention.

This device comprises an apparatus which is indicated as a whole by 3, and includes two electrodes 4 and 5 placed opposite each other, and which are included in a small chamber 7 communicating at the top and at the bottom of this chamber by narrow orifices 8 and 9 with a vessel 10. This vessel, which is preferably made of metal and provided with radiating fins 11 for its cooling, can be filled through a stopper 12, preferably provided with a vent hole, with an electrolyte, in such a way that the chamber 7 is filled with this electrolyte. In addition, this chamber 7 communicates with the atmosphere through a small vent hole 13.

One of the conductors connected to one of the terminals 2 and leading to the installation 1 terminates at the electrode 4 and starts off again from the electrode 5. From this conductor, on the installation side of the apparatus 3, there is connected in shunt the holding coil winding 14 of a minimum current circuit-breaker comprising a contact blade 15 and a restoring member, for example a spring 16. A push-button 17 allows the blade 15 to be closed by hand. This push-button may, of course be replaced by any kind of electro-magnetic remote control device acting on the contact blade.

The arrangement which has just been described operates in the following way:

When the contact blade 15 is closed by hand or through an auxiliary circuit, the current passing from the electrode 4 to the electrode 5 supplies the installation 1. When this current does not reach an excessive value, the contents of the chamber 7 remain liquid and the resistance r

offered by the electrolyte to the passage of the current is small. In consequence, the voltage U at the terminals of the winding 14 is almost the same at the nominal voltage U_0 . The current which passes through the winding 14 thus holds the contact attracted and the installation operates in the normal way. The small amount of heat dissipated in the chamber 7 causes a circulation by thermosiphon action in the direction of the arrow inside the vessel 10; this heat is dissipated by the vessel and there are thus established fixed conditions of operation of the installation.

If, for any reason whatever, the value of the current taken by this installation increases, the amount of heat developed in the chamber 7 reaches such a value that a portion of the liquid becomes vaporised. This vaporisation forces the liquid in this chamber towards the reservoir 10 and, in consequence, the resistance between the electrodes increases very rapidly as shown in Fig. 2, from the value r to a certain value R which can be many times greater. A portion of the vapour is able to escape through the vent hole 13, and it is thus possible to regulate the rate of increase in this resistance as a function of the overload current, and, in consequence, the rate of decrease of the current value in the whole of the installation.

The increase in resistance in the apparatus, causes a voltage drop at the terminals of the winding 14, in such a way that the force of attraction which holds the contact blade 15 diminishes, and the restoring force, supplied by the member 16 which acts on this contact, can open the latter and thus open the circuit.

This operation is shown in detail in the diagram of Fig. 3.

When, at the instant t_0 , the current value begins to increase more or less rapidly from its normal value I_n , this current reaches the threshold value I_s from which moment the liquid contained in the chamber 7 begins to vaporise. Between the times t_1 and t_2 , during which this vaporisation takes place, the current value does not however very greatly exceed I_s , since the apparatus is self-regulating owing to the fact that the more rapidly the current increases, the more the rate of vaporisation increases. The small size of the orifices 8 and 9 prevents any rapid return of the liquid to the chamber 7, and the resistance between the electrodes thus remains at a high value and the current value in the circuit of the installation decreases very rapidly and becomes zero at the moment t_3 , when the minimum current circuit-breaker has opened.

By making a suitable choice of the breaking voltage of the circuit-breaker and also of the time delay of its operation, the breaking of the circuit can be effected at a current value I_c , which may be very much lower than the current I_n .

The circuit-breaker device in accordance with the invention thus ensuring the opening of the circuit at a current value less than the normal current, the device may be used with advantage in the case of voluntary interruption of the circuit of the installation. To this end there may be provided an arrangement which applies at will a systematic overload to the supply circuit of the installation 1, for example a circuit 46 consisting of a resistance of low value which may be put into service by means of a push-button 47. When this button is depressed, a momentary overload is produced which causes the circuit-breaker device to operate.

In addition, the minimum current circuit-breaker continues to play, in an installation of this kind, its usual role of providing a protection against supply circuit faults.

However, when the overload does not arise from a short-circuit, but tends to be produced progressively, the operation of the apparatus 3 may become pulsating, or in other words there is produced a partial vaporisation of the liquid in the chamber 7 which results in a reduction in the current value in the circuit of the in-

stallation, and then a return of the liquid into this chamber which tends to restore this current to its initial value. The voltage across the terminals of the winding 14 has, in this case, a pulsating nature without necessarily falling to the value which would cause the operation of the minimum current circuit-breaker. This pulsatory variation of voltage may be detected for example, by means of an incandescent lamp 43 arranged in series with the winding 14.

In the embodiment shown in Fig. 4, a tank with fins 18 filled with electrolyte contains at the same time in its upper portion an apparatus 3 forming part of a circuit-breaker device in accordance with the invention and, in its lower portion, a liquid resistance rheostat 19, intended, for example, for starting up a motor, in the present case of the single-phase type.

The rheostat may be of any particular kind. In the example shown, this rheostat consists of an insulating rotor 20 which can be moved by means of a shaft 21 and a button 22 inside an insulating cylindrical casing 23 provided with communication holes 24 (which may be adjustable) leading to the interior of the tank 18. The rotor 20 carries two electrodes 25 having the form of sectors and inter-connected by a conductor 26, whilst two electrodes 27 in the form of a sector of a cylinder are provided against the internal wall of the casing 23, the electrodes 25 being arranged opposite the electrodes 27. The electrodes 27 are connected by means of insulated conductors 28 to two terminals 29 of the lid 30 of the tank through which passes the shaft of the rotor 21.

Such a rheostat can operate either as a manually variable rheostat, by varying the opposite surfaces of the electrodes or, more simply, in the case of a motor, as an automatic rheostat, in the manner described in the patent referred to in the introduction to this specification. In practice, as in the case of the apparatus 3 combined with the circuit-breaker device in accordance with the invention, there is produced in such a rheostat a powerful rush of current at the moment of starting up this motor, and this current surge causes a partial vaporisation of the liquid, so that the resistance of the quantity of the liquid which is contained between the electrodes 25 and 27, varies and adjusts itself automatically to the value necessary for the starting up of the motor by a partial expulsion of the liquid referred to.

The apparatus 3 which is located in the upper portion of the tank 18 is constructed in a similar manner to that shown in Fig. 1. However, in this case, the electrodes 4 and 5 are cylindrical and the chamber 7 is of annular shape. The electrode 4 can be connected through the conductor 31 and the terminal 32 to the current input circuit, whilst the electrode 5 is connected to one of the conductors 28, the minimum current circuit-breaker being in that case connected between the terminal 29 of the conductor 28 and the other wire of the supply line. A tubular member 33, closed by a plug 34, is provided for filling up the tank with liquid and an insulating plate 35, supported for example by the short struts 36 prevents contact between the various terminals, the operating button 22 having its shaft passing through this plate.

In addition to its function as a circuit-breaker, similar to that which has been described in respect of Fig. 1, the apparatus 3 also constitutes a means of controlling the level of the electrolyte. In fact, if the level N of this electrolyte falls, the apparatus 3 is insufficiently filled and in consequence the vaporisation of the liquid which it contains occurs more rapidly, and this vaporisation causes the minimum current circuit-breaker to operate. It should further be observed that when the temperature of the electrolyte rises, the threshold current value I_s , which corresponds to the vaporisation of the contents of the apparatus 3 remains roughly constant up to a certain temperature T_1 , and then decreases very rapidly from that temperature T_1 to the temperature T_2 , which is the boiling point of the electrolyte. The circuit-breaker

ensures in this case a thermostatic control of the temperature of the tank since in practice it prevents this temperature from rising above the value T_1 .

The circuit-breaker device in accordance with the invention is also capable of application with advantage in all cases of distribution of alternating current and enables generally a considerable simplification in means of protection against overload to be obtained.

In particular Fig. 7 shows a form of application which can be used in a general way, in the case of polyphase current consisting of n phases and n conductors and enables all the phases to be interrupted, no matter which phase is at fault, by means of a single minimum current circuit-breaker. The apparatus 3 comprises in this case $n-1$ chambers superposed on each other and communicating with each other, whilst the circuit-breaker is connected between the first and the last of the phases, that is to say the phase which is connected to the top chamber of the apparatus 3 and that which does not pass through the said apparatus.

The apparatus 3 comprises the electrodes 4a, 5a and 4b, 5b which, in the example shown, are of cylindrical shape. The annular chambers 7a, 7b, which communicate with each other through the passage 37 and are, as in previous cases, associated with the vessel 10 (which forms a reservoir for the electrolyte and a means of dissipating heat) through the passages 8a, 8b, 9a, 9b. The dimensions of the passages 37 are sufficiently small so as not to cause any appreciable electrical losses by reason of its connection in shunt between the supply phases 38a and 38b of the installation 1 (phases, the current of which passes through the chambers 7a and 7b) but the passages are however sufficiently large to allow free passage of the vapour from the chamber 7b to the chamber 7a. At the top of the apparatus, there are provided vent holes 13 as in previous cases.

The operation of this assembly is as follows:

If, by reason of an overload appearing on one of the phases 38a or 38b, a vapour is produced in one of the chambers 7a or 7b, this vapour accumulates in the chamber 7a and causes a voltage drop across the terminals of the winding 14 which is connected between the phases 38a and 38c. The three contact blades 15a, 15b and 15c thus open. It is clear that, if the overload occurs on the phase 38c, the two phases 38a and 38b then produce in their corresponding chamber a vapour and the operation is exactly the same.

In the case of Fig. 9, the supply system of the installation 1 consists of a two-phase four-wire network. Between the terminals 39 and 40 on the one hand, and 41 and 42 on the other hand, of this installation, there will for example be established an alternating potential of 220 volts, while between two homologous conductors such as 39 and 41, by reason of the phase-quadrature of the two first potentials, there is an alternating voltage of 310 volts. In this case, two units, each comprising an apparatus 3, are connected in series in the lines coming from the terminals 39 and 41 and on the other side of the units 3, these conductors are joined together to the circuit of the winding 14 of the minimum current circuit-breaker, which breaks the four conductors by means of its blade contact 15, for example on the supply side of the units 3.

An overload which occurs in one of the circuits connected to the terminals 39, 40 on the one hand, or 41, 42 on the other hand, gives rise to a voltage drop across the terminals of the winding 14 and causes the circuit-breaker to operate.

In the description which has been given, the vent holes 13, and also the vent holes of the vessel 10, have been supposed to be permanently open, which necessitates a periodic correction (in general by means of distilled water) for the evaporation of the electrolyte. In order to avoid this necessity, the vents can be provided with small flap-valves, or even with tear-off stoppers which

only need to be replaced when the circuit-breaker device has operated. It may also be arranged that the vents 13 discharge into the vessel 10 above the level of the liquid, in order to provide for condensation and recovery of the vaporised liquid. In this case, over-pressure safety devices may be provided to protect the vessel itself.

It will be clearly understood that modifications may be made to the circuit-breaker device which has been described above, particularly as concerns the use of equivalent technical means, without thereby departing from the scope or from the spirit of the present invention.

What I claim is:

1. In a supply circuit of an electrical installation, a cut-out device comprising in combination a liquid-resistance apparatus series-connected with respect to said supply circuit and including at least two oppositely-disposed electrodes forming between them a chamber of small volume, a vessel adapted to contain conducting liquid, duct means between said vessel and said chamber offering resistance to the flow of said liquid, and a minimum-current circuit-breaker having a holding coil shunt-connected with respect to said supply circuit between said apparatus and said installation, and having power contacts connected in said supply circuit on the supply side of said holding coil.

2. A cut-out device according to claim 1 further comprising a vent-passage at the upper part of the chamber for the exhaust of vapors of the liquid contained therein when and if said liquid is at least partly vaporized.

3. A cut-out device according to claim 1 wherein the vessel containing conducting liquid forms a part of a liquid-resistance rheostat, the chamber of said apparatus being located at the upper part of said vessel.

4. A cut-out device according to claim 1 further comprising a luminous warning signal device connected in series with the holding coil of the circuit-breaker.

5. A cut-out device according to claim 1 wherein the supply circuit is a single-phase alternating current circuit having two wires, the liquid-resistance apparatus being in series with one of said wires and the holding coil of the circuit-breaker being connected in shunt across said two wires.

6. A cut-out device according to claim 1 wherein the supply circuit is a polyphase alternating current circuit

having n phases and n wires and the liquid-resistance apparatus includes $(n-1)$ chambers arranged one upon another and in fluid communication with one another, each of said chambers being associated with one of said wires so that the current in said wire flows through said chamber; the holding coil of the circuit-breaker being connected in shunt between the wire associated with the uppermost chamber and the nth free wire.

7. A cut-out device according to claim 1 wherein the supply circuit is a two-phase alternating current circuit having four wires and the liquid-resistance apparatus includes two chambers, two wires corresponding to different phases being respectively associated with a chamber, the operating winding of the circuit-breaker being connected in shunt between said two later-mentioned wires.

8. A cut-out device according to claim 2 further comprising valve means for controlling the vent-passage.

9. Electrical supply circuit protection apparatus comprising line terminals for connection to a current supply source and load terminals for connection to an electrical utilization installation, a liquid resistance device having two compartments connected by channels and containing a vaporizable liquid electrolyte, a pair of electrodes in one of said compartments defining between them a space within which liquid will be vaporized by the passage of excessive current; a circuit breaker comprising a holding coil, power contacts and a movable member associated with said holding coil to maintain said power contacts closed when the current in said coil exceeds a predetermined value; means connecting said electrodes, said holding coil and said power contacts in a series circuit with said line terminals, and means connecting said load terminals in shunt to said holding coil.
